UNITED STATES PATENT OFFICE.

HENRY S. WALBRIDGE, OF NORTH BENNINGTON, VERMONT.

DESIGN FOR A BRIDGE-PIECE FOR STEREOSCOPES.

SPECIFICATION forming part of Design No. 25,210, dated March 3, 1896.

Application filed December 27, 1895. Serial No. 573,542. Term of patent 7 years.

To all whom it may concern:

Be it known that I, HENRY S. WALBRIDGE, a citizen of the United States, residing at North Bennington, county of Bennington, State of Vermont, have invented and produced a new and original Design for a Bridge-Piece for Stereoscopes, of which the following is a specification, reference being had to the accompanying drawings, wherein—

Figure 1 is a plan view of a bridge-piece for stereoscopes embodying my novel design, and Fig. 2 is an edge view of the same.

My newly-designed bridge-piece A is of the general form of a quadrilateral-plane figure, having an indentation A' in one edge and an ornamental lip projection B on the edge opposite such indentation. The lip projection

is shown curved in outline, as are the edges of the indented portion.

The leading feature of the design is the bridge-piece for stereoscopes having the indentation in one edge and the lip projection on the edge opposite such indentation.

What I claim as new, and desire to secure by Letters Patent, is—

The design for a bridge-piece for stereoscopes herein shown and described.

In testimony whereof I have hereunto set my hand this 26th day of December, 1895.

HENRY S. WALBRIDGE.
